United States Patent Office

Des. 217,150
Patented Apr. 14, 1970

217,150

FLUID HEAT EXCHANGER

William F. Shriver, Waynesboro, Pa., and Raymond A. Lo Turco, Columbus, Ind., assignors to Frick Company, Waynesboro, Pa., a corporation of Pennsylvania

Filed Jan. 2, 1968, Ser. No. 10,016

Term of patent 14 years

Int. Cl. D23—04
U.S. Cl. D23—153

FIG. 1

FIG. 2

FIG. 1 is a perspective view of the fluid heat exchanger embodying our new design, the opposite side having substantially the same appearance.

FIG. 2 is a top plan view of the heat exchange apparatus shown in FIG. 1.

The dominant features of our design reside in the full line portions.

I claim:

The ornamental design for a fluid heat exchanger, as shown and described.
